(57) **CLAIM**

The ornamental design for a bath for a handicapped person, as shown and described.

DESCRIPTION

FIG. 1 is a perspective view of a bath for a handicapped person showing our new design;

FIG. 2 is a top plan view thereof;

FIG. 3 is a front elevation view thereof;

FIG. 4 is a right side view thereof;

FIG. 5 is a bottom plan side view thereof;

FIG. 6 is a rear elevation view thereof;

FIG. 7 is a left side view thereof;

FIG. 8 is a perspective view thereof showing a state where a bathtub cover opens; and,

FIG. 9 is a perspective view thereof for reference which shows a state where the bathtub is retracted when it is not used.
